Letters Patent No. 3613. Dated Decr 18 1864.

Design for the Plates of a Stove.

The schedule referred to in these Letters Patent and making part of these

shall whom it may concern.

Be it known that I, Nicholas G. Wedder, of the City of Troy, in the County of Rensselaer, and State of New York, have invented, or produced a certain new and original ornamental Design, for Stove Plates; and I do hereby declare that the following is a full, clear and exact description of the same, reference being had to the accompanying photographs, affix four stove plates each bearing my said ornamental design.

This ornamental design consists in the arrangement of the particular compound ornament marked Q, upon a plain surfaced panel marked R, with a rounded top, upright parallel sides Q, S, and a flat bottom L, so as to present the appearance shown by the aforesaid accompanying photographs.

What I claim as new and of my invention or production and desire to secure by Letters Patent is the above described ornamental design for Stove plates.

In testimony whereof I have hereunto set my hand,
this Fourteenth day of November eighteen hundred and sixty four.
